US00D784383S

(12) **United States Design Patent** (10) Patent No.: **US D784,383 S**
 Hong et al. (45) Date of Patent: ** Apr. 18, 2017

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Seongkook Hong**, Seoul (KR); **Jincho Choi**, Seoul (KR); **Cheolhoon Kang**, Seoul (KR)

(73) Assignee: **SAMSUNG ELECTRONICS CO., LTD.**, Gyeonggi-Do (KR)

(**) Term: **15 Years**

(21) Appl. No.: **29/547,306**

(22) Filed: **Dec. 2, 2015**

(30) **Foreign Application Priority Data**

Sep. 2, 2015 (KR) 30-2015-0044292

(51) **LOC (10) Cl.** **14-04**

(52) **U.S. Cl.**

USPC **D14/486**; D14/492

(58) **Field of Classification Search**

USPC ..... D10/70; D14/138 R, 240, 30, 344, D14/485-495

CPC G06F 3/04886; G06F 2203/04807; G06F 3/04842; H04M 1/2477

See application file for complete search history.

(57) **CLAIM**

We claim, the ornamental design for a display screen or portion thereof with graphical user interface, as shown and described.

DESCRIPTION

FIG. 1 is a front view of a display screen or portion thereof with graphical user interface showing our new design according to a first embodiment; and,

FIG. 2 is a front view of a display screen or portion thereof with graphical user interface showing our new design according to a second embodiment.

The broken line showing of the alphanumeric characters, symbols, and display screen in the Figures is for environmental purposes only and forms no part of the claimed design.

1 Claim, 2 Drawing Sheets
